H. C. DINDINGER

SHEAVE LOCK

Filed Dec. 11, 1922

INVENTOR

Harry G. Dindinger,
By Baker & Mackenzie,
ATTORNEYS

UNITED STATES PATENT OFFICE.

HARRY C. BINDINGER, OF MOLINE, ILLINOIS.

SHEAVE LOCK.

Application filed December 11, 1922. Serial No. 606,074.

To all whom it may concern:

Be it known that I, HARRY C. BINDINGER, a citizen of the United States, residing at Moline, in the county of Rock Island and State of Illinois, have invented a certain new and useful Improvement in a Sheave Lock, of which the following is a full, clear, and exact description, reference being had to the accompanying drawings.

This invention is concerned particularly with means for locking a rope or cable to a sheave and has for one of its objects the provision of a simple and efficient locking mechanism which may be satisfactorily operated on ropes or cables of various sizes.

An additional object includes the construction of a locking mechanism which may be readily actuated by swinging the free end of a cable relatively to the sheave, and without slackening the free end during the swinging operation.

A still further object is the provision of a locking device which may be so mounted upon the frame which supports the sheave so that the cable may be passed over the sheave without necessitating a threading of the free end of the cable between the sheave and frame.

In carrying out my invention, I employ a brake shoe or locking dog, which is mounted to swing over a pulley sheave and against the rope or cable which travels over the sheave, and I mount the mechanism for actuating the shoe upon a frame in which the pulley is carried. The direction in which the shoe is movable for locking purposes is the same as the direction of pull on the cable, whereby the shoe tends to remain in locked position. To facilitate the operation of the shoe I so arrange the actuating mechanism that the free end of the cable or rope may be used as a lever to control the position of the shoe.

The means for carrying out the above objects will be more fully set forth in the following description, which pertains to the accompanying drawings, and the essential characteristics will be summarized in the claims.

In the drawings, Fig. 1 is a side elevation of a sheave having a lock associated therewith embodying my invention; Fig. 2 is a similar view showing the lock in open position; Fig. 3 is a section taken through the lock on the line 3-3 in Fig. 1; while Fig.

4 is a longitudinal section taken on the correspondingly numbered line in Fig. 3.

In the various figures, I have shown a sheave 10 which is rotatably mounted upon a shaft 11, which in turn is journaled in a frame. This frame is shown as a U-shaped member having sides 13 and 14, which straddle the sheave and provide a suitable support for the locking mechanism as will be hereinafter described. One side of the frame, as at 14, may be extended beyond the locking mechanism and be provided with an enlargement 15. In the enlargement I have shown an opening 16 together with a retaining pin 17 for holding the sheave in a convenient support 18, as indicated in Fig. 1.

The frame supporting the sheave also carries the lock. This lock comprises a shoe 19 which is pivotally mounted, as at 20, to a locking lever 21. This shoe is arranged to be moved relatively to the sheave and to be turned during such movement in such manner that the clamping face 22 remains parallel to the periphery of the sheave. To effect this movement, I have shown the shoe as having an extension 23, which is provided with a slot 24. This slot co-operates with the shaft 11 to maintain the clamping face of the shoe parallel to the sheave whenever the locking lever 21 is moved relatively to the sheave. The two positions of the shoe showing the movement of the slot 24 is shown in Fig. 4 at 24 and 24^a.

The locking lever which supports the shoe is shown as an irregularly shaped member which is formed at one end, as at 25, to receive the pin 20 and at the other end, as at 26, to receive a shaft 27 which is carried by the sheave frame. I have shown this lever rigidly attached to the shaft 27 by means of a pin 28, and I have also shown a spring 29 which surrounds the lower part of the locking lever and is attached at one end to the lever and at the other end to the frame so as normally to urge the locking lever into clamping position. This position is shown in full lines in Fig. 4.

To permit movement of the locking lever with relation to the sheave, I provide an arcuate slot 30 through which the shaft 11 may extend. In this way, arcuate movement of the locking lever is limited and is controlled for receiving various sizes of ropes which pass over the sheave.

With the mechanism heretofore described, a cable B which passes over the sheave is normally locked by the spring 29. Accordingly, to release the cable it is only necessary to move the locking lever 21 against the force of the spring to the position indicated by the broken lines in Fig. 4. To accomplish this movement without necessitating considerable inconvenience and power, I provide a mechanism which may be actuated by a single swinging movement of the free end C of the cable.

The means for actuating the locking lever 21 is shown as a rock lever 35 which is pivotally mounted on the shaft 11 outside the sheave frame and is bifurcated, as at 36, to receive the crank arm 37 which may form an extension of the shaft 27. The outer end of this rock lever carries a pin 38 which moves in an arcuate slot 39 in a tripping lever 40. This tripping lever is shown as pivoted at 41 to the side 14 of the frame. The free end of the tripping lever extends beyond the sheave and may be provided with a pair of oppositely disposed cable guides 42 and 43 which extend inwardly toward the sheave.

Assuming that the cable B is placed around the sheave, and that the free end C is inserted between the guides on the tripping lever, and further that the shoe is in locked position as shown in Fig. 1, then to release the cable it is only necessary to swing the tripping lever in the direction indicated by the arrow D in Fig. 1. This is accomplished by swinging the free end of the rope which passes through the guides. When the tripping lever is swung as indicated, then the pin 38 is raised by the slot 39 whereupon the forked end of the rock lever is swung from the position indicated in Fig. 1, to the position indicated in Fig. 2. Thus the crank arm 37, locking lever 25, and shoe 19 are simultaneously moved downwardly and are maintained in such position, until the cable is swung backwardly to the position indicated in Fig. 1. Since the load is in the direction indicated by the arrow E in the various figures, then as soon as the free end of the cable is swung backwardly to its original position, the shoe is brought into contact with the cable in a direction corresponding to that of the load. Thus the brake shoe is moved to locking position whenever the area of contact between the cable and sheave is decreased and is released whenever the area of contact is increased.

An advantage of a sheave lock constructed according to my invention is that the cable may be placed over the sheave without threading the free end thereof through the frame. This follows by reason of the fact that the side 13 of the frame terminates short of the periphery of the sheave, and also for the reason that the locking shoe, together

with the associated mechanism, is carried by the opposite side of the frame. This is particularly useful whenever it is desired to use the lock for holding comparatively long cables.

I claim:—

1. In combination, a sheave, a supporting frame therefor, a locking shoe mounted on the frame and movable relatively thereto, and means for maintaining the clamping face of the shoe concentric to the periphery of the sheave during such movement.

2. In combination, a sheave, a brake shoe movable toward and away from the sheave, means for maintaining the clamping face of the brake shoe during such movement concentric to the periphery of the sheave, a flexible load supporting member passing over the sheave, and mechanism engaging the free end of the member and connected with the shoe whereby variations in the area of contact between the member and sheave effect relative movement between the shoe and said sheave.

3. In combination, a sheave, a supporting frame therefor, said frame having one side open, and a locking shoe movable relatively to the sheave and frame, and means for mounting the shoe on the frame to permit a flexible hoisting member to be passed over the sheave adjacent the open side of the frame without threading the free end of the member through the sheave.

4. In combination, a sheave, a frame therefor, a lever pivotally mounted on the frame, a brake shoe associated with said lever, and means associated with the lever for retaining the clamping face of the shoe concentric with the periphery of the sheave whenever the lever is moved relatively to the frame.

5. In combination, a sheave, a supporting member therefor, a lever pivoted to said member remote from the axis of said sheave, a shoe carried by said lever, a second lever cooperating with the first mentioned lever for controlling the operation of said shoe, and means for normally urging the first lever so as to bring the shoe into locking position.

6. In combination, an open sided frame, a sheave journaled therein, a lever pivotally mounted within the frame beyond the periphery of the sheave, a brake shoe carried by the lever at the side of the sheave opposite the pivotal connection of said lever, and means for urging the shoe into locking position.

7. In combination, a sheave, a supporting frame therefor, a brake shoe mounted within the frame, and mechanism including a pair of cooperating levers for swinging the brake shoe relatively to the sheave.

8. In combination, a sheave, a supporting frame therefor, a lever pivotally mounted

to swing within the frame, a brake shoe carried by the lever, and mechanism including members having pin and slot connections for actuating the first mentioned lever 5 to operate said shoe.

9. In combination, a frame, a sheave journaled in said frame, a brake shoe, a rock lever pivoted to the frame so as to swing about the axis of the sheave, means 10 whereby the free end of the cable passing over the sheave may actuate one of said levers, and mechanism controlled by the other end of said lever for moving said shoe relatively to the sheave.

15 10. In combination, a frame, a sheave journaled therein, a flexible load engaging member passing over the sheave, a lever having one end thereof pivotally mounted on the frame, a brake shoe carried by the 20 other end of the lever and adapted to clamp said member to the sheave, a rock lever pivoted to said frame and operatively connected with the shoe carrying lever, and a tripping lever operatively connected with the rock lever, whereby movement of said 25 rock lever in one direction effects a corresponding movement of the shoe relatively to the sheave.

11. In combination, an open sided frame, 30 a shaft extending therethrough, a sheave journaled on the shaft within the frame, a lever pivotally mounted on the frame and having an arcuate slot co-operating with said shaft for limiting the movement of the 35 lever relatively to the frame, a brake shoe carried by the lever, said shoe having an extension projecting beyond the shaft and intermediate the lever and sheave, said extension having a slot co-operating with said 40 shaft whereby movement of the lever relatively to the frame maintains the clamping face of said shoe concentric to the periphery of the sheave.

12. In combination, an open sided frame, 45 a shaft extending therethrough, a sheave journaled on the shaft within the frame, a lever pivotally mounted on the frame and

having an arcuate slot co-operating with said shaft for limiting the movement of the lever relatively to the frame, a brake shoe 50 carried by the lever, said shoe having an extension projecting beyond the shaft and intermediate the lever, said extension having a slot co-operating with said shaft whereby movement of the lever relatively 55 to the frame maintains the clamping face of said shoe concentric to the periphery of the sheave, a rock lever pivoted on said shaft outside the frame, said rock lever being operatively connected at one end with the 60 shoe carrying lever, and means whereby the free end of a load engaging member passing over the end of the sheave may actuate the rock lever to control the operation of said shoe. 65

13. In combination, an open sided frame, a shaft extending therethrough, a sheave journaled on the shaft within the frame, a load engaging member passing over the sheave, a lever pivotally mounted on the 70 frame and having an arcuate slot co-operating with said shaft for limiting movement of the lever relatively to the frame, a brake shoe carried by the lever, said shoe having an extension projecting beyond the shaft 75 and intermediate the lever and sheave, said extension having a slot co-operating with said shaft whereby movement of the lever relatively to the frame maintains the clamping face of said shoe concentric to the periphery of the sheave, a rock lever pivoted on said shaft outside the frame, said rock lever being operatively connected at one end with the shoe carrying lever, a tripping lever having one end pivoted to the frame 80 and having the free end formed to receive the free end of the load engaging member, and means connecting the rock lever and tripping lever whereby movement of the free end of the tripping lever controls the 85 operation of said shoe. 90

In testimony whereof, I hereunto affix my signature.

HARRY C. DINDINGER.
